ABSTRACT OF THE DISCLOSURE

A felting needle having a body portion of polygonal cross section in which a pair of adjacent body side surfaces form a corner edge extending length-wise of the needle, a barb in the corner edge, and a recess extending from the pointed end of the needle to the barb defined by a longitudinal surface disposed entirely inward and substantially parallel to the corner edge.

My present invention relates to improvements in felting needles and more particularly to fine gauge felting needles.

In felting needles, and especially fine gauge felting needles, it is essential that the barb or barbs project into the slipstream of fibers for effectively interlacing the fibers. The present invention is directed to a construction in which rather than attempt to provide a desired barb projection resides in providing any suitable barb and open up the throat area for the barb for the desired fiber accessibility.

Accordingly, it is an object of my present invention to provide a felting needle in which the body is provided with a barb carrying ridge having a barb therein adjacent the pointed end of the needle, and in which an open throat or recess is defined by a longitudinal surface disposed entirely inward and substantially parallel to the barb carrying ridge extending from the pointed end of the needle to the barb.

I propose to achieve the foregoing object by providing a felting needle having a body portion of polygonal cross section, and in which at least one pair of adjacent side body surfaces extend angularly toward each other to define a ridge extending lengthwise on the body portion. In a preferred embodiment of the invention the needle body is preferably of triangular cross-section with one or more ridges containing at least one barb at the pointed end of the needle, and in which, as aforesaid, an open throat or recess between the barb and the pointed end of the needle is defined by a longitudinal surface disposed entirely inward and substantially parallel with the corner edge.

A preferred embodiment of the invention will now be described in connection with the accompanying drawing in which—

FIGURE 1 is an elevational view of a felting needle of my present invention;

FIGURE 2 is a greatly enlarged side elevational view of the body portion of the felting needle adjacent its pointed end;

FIGURE 3 is a cross sectional view taken substantially along the line 3—3 on FIGURE 2; and

FIGURE 4 is a cross sectional view taken along the line 4—4 on FIGURE 2.

Referring now to FIGURE 1 of the drawing, there is shown a felting needle 5 constructed in accordance with

2

the principles of my present invention which comprises a body, indicated generally at 6, and a shank, indicated generally at 7. The lower end of the body is pointed as at 8 to facilitate penetration of fibrous material to be compacted in a conventional manner. The upper end of the needle may be bent substantially at right angles to the shank 7 to provide a securing element or ear 9 for clamping between a base member and a clamping member of a conventional needle plate. As is well known, such a needle plate is adapted to support a plurality of felting needles, such as shown in FIGURE 1, which is reciprocation of the plate in the felting machine effects the interlacing and compacting of loose fibrous materials.

The felting needles of my present invention may be made of any ordinary or conventional needle stock having the necessary mechanical strength as, for example, steel wire. In making up the needles of my present invention, preferably originally round steel wire stock is used from which a suitable length is cut to form a needle with a portion thereof, which is to become the body of the needle, swaged as hereinafter described.

Upon reference to FIGURE 4, the cut length of steel stock 10 for the needle may be disposed between a pair of split dies disposed on opposite sides of the stock which are advanced toward each other to form the stock 10 at the body portion of the needle into substantially triangular configuration in cross-section and defined by body surfaces 14, 15 and 16. The adjacent pairs of such side body surfaces extend angularly toward each other. The aforementioned dies are suitably shaped so as to form a lengthwise extending corner edge or ridge, as indicated at 17, lying laterally outwardly of two adjacent side body surfaces, such as side body surfaces 14 and 15. Additional corner edges or ridges may, of course, be formed at the intersections defined by any adjacent and intersecting pair of the body surfaces 14, 15 and 16. After formation of one or more corner edges or ridges 17 on the body of the felting needle as above described a barbing recess as indicated at 22 in FIGURE 2, together with a barb, such as at 23, may be formed at the end of the needle adjacent its pointed end 8.

The barb 23 may be of any desired size and configuration and may, for example, be formed by displacing material in forming the throat or recess 22. According to the present invention, the throat or recess 22 is defined by a longitudinal surface, as indicated at 24 in FIGURES 2 and 3, which is disposed entirely inwardly and substantially parallel with the corner edge or ridge 17 and with such longitudinal surface 24 extending to the pointed end 8 of the needle. As previously noted, if desired, other of the corner edges of a body of polygonal cross section of a felting needle may be formed with throat or recess 22 defined by a longitudinal surface, such as at 24, between the barb 23 and the pointed end of the needle.

While a preferred form of the invention has been shown and described, it will be obvious that changes and modifications may be made therein without departing from the spirit and scope of the invention.

The invention claimed is:

1. A felting needle having a body portion of polygonal cross section in which a pair of adjacent body side surfaces extend angularly toward each other to form a longitudinal corner edge, said body portion having a pointed end, a barb in said longitudinal edge, and a recess at said

3

barb defined by a longitudinal surface disposed entirely inward and substantially parallel to said corner edge.

2. The felting needle of claim 1 in which said body portion is of triangular configuration.

3. The felting needle of claim 1 in which said longitudinal surface of said recess extends between said pointed end of said body portion and said barb.

4. The felting needle of claim 1 in which said body portion is of triangular configuration, and in which said

4

longitudinal surface of said recess extends between said pointed end of said body portion and said barb.
